(No Model.)

G. B. QUIGLEY.
COVER FOR JARS.

No. 542,807.

Patented July 16, 1895.

UNITED STATES PATENT OFFICE.

GEORGE B. QUIGLEY, OF BRADDOCK, PENNSYLVANIA.

COVER FOR JARS.

SPECIFICATION forming part of Letters Patent No. 542,807, dated July 16, 1895.

Application filed March 29, 1895. Serial No. 543,691. (No model.)

To all whom it may concern:

Be it known that I, GEORGE B. QUIGLEY, a citizen of the United States, residing at Brad-
dock, in the county of Allegheny and State
of Pennsylvania, have invented certain new
and useful Improvements in Covers for Jars,
Crocks, &c., of which the following is a speci-
fication.

The object of my said invention is to pro-
vide a combined cover and handle for crocks,
jars, and such like vessels, whereby when the
cover and its fastening devices are in place
the whole structure may be carried by means
of the handle, and which by easy manipula-
tion may be changed so that the cover may be
removed.

A structure embodying my said invention
will be first fully described, and the novel fea-
tures thereof then pointed out in the claims.

Referring to the accompanying drawings,
which are made a part hereof, and on which
similar letters of reference indicate similar
parts, Figure 1 is a perspective view of an ordi-
nary shallow earthenware jar or pan pro-
vided with a cover and fastening devices em-
bodying my said invention with said devices
in their closed-in or fastened position; Fig.
2, a similar view with the fastening devices
raised and the cover ready to be removed;
Fig. 3, a top or plan view with the parts in
the position shown in Fig. 1; Fig. 4, a central
sectional view on the dotted line 4' 4 in Fig.
3; Fig. 5, a perspective view similar to Fig. 2,
illustrating an alternative construction; and
Fig. 6 a fragmentary view showing the con-
struction illustrated in Fig. 5, but otherwise
similar to a portion of Fig. 4.

In said drawings the portions marked A
represent the vessel to which my invention is
to be applied; B, the cover; C, a clamping-
spider or fastening device, and D the handle.

The vessel A may be any ordinary vessel
having an offset ring, rim, or projection of any
kind, as at a—such as a crock, jar, or other
earthenware vessel. That illustrated is a com-
paratively shallow vessel, being an earthen
crock or pan.

The cover B in itself is a plain cover adapted
to fit over the top of the vessel A and may be
of any suitable material—such as wood. It
carries on its outer edges spring-catches b,
which are adapted to extend down alongside

the vessel to below the offset or rim or de-
pression thereon and when forced inwardly
by any means to engage with said rim or off- 55
set, so that said cover and the vessel are there-
by connected together, whereby when the
cover is lifted by means of the handle the ves-
sel will also be lifted. The engaged position
is illustrated in Figs. 1, 4, and 6 and the dis- 60
engaged position particularly by Figs. 2 and
5. These catches are preferably formed of
spring metal, and so formed that they will
normally stand in disengaged position until
forced in by the clamping or fastening de- 65
vice C.

The clamping or fastening device C has sev-
eral arms, (four are shown,) and may have as
many or as few as may be desired. The ends
c of these arms extend down vertically, and 70
in the form shown in Figs. 1 to 4, inclusive,
carry a ring C' thereon, which comes in con-
tact with the spring-catches b on the cover B
and force them into engagement with the rim
or offset a on the vessel A. In the form shown 75
in Figs. 5 and 6 the spring-catches b and spi-
der-arm ends c are arranged to register, so
that the ring C' is dispensed with. The han-
dle D is secured to the cover B centrally and
passes also up through the center of the fas- 80
tening device C. As shown most plainly in
Figs. 4 and 5, a recess is cut in one side of
the middle part of said spider, and said han-
dle is hinged to fold down into said recess, so
that when folded said handle forms also a 85
lock for said fastening device.

This whole device is very simple and forms
a very convenient means whereby vessels of
the character indicated can be handled and
carried and their covers removed and securely 90
attached at pleasure. The handle normally
serves to prevent the clamping or fastening
device from being entirely removed, as clearly
shown.

Having thus fully described my said inven- 95
tion, what I claim as new, and desire to secure
by Letters Patent, is—

1. The combination, with a vessel, as A,
having an offset or rim a, of a cover B hav-
ing catches b attached to its edge, a spider- 100
like clamping or fastening device C adapted
to operate said catches, and a handle secured
to the cover and forming a guide for said fas-
tening device.

2. The combination of a vessel A, a cover B having catches thereon, a clamping or fastening device C, and a handle D secured to said cover and passing through an opening 5 in the center of said clamping device, whereby the latter is guided or held in place, substantially as shown and described.

3. The combination of a vessel, a cover thereto, catches on said cover adapted to engage with said vessel, a clamping device C adapted to operate said catches, a hinged handle D secured to said cover and passing

through an opening therein, and adapted to be folded and thus lock said clamping or fastening device, substantially as shown and described.

In witness whereof I have hereunto set my hand and seal, at Braddock, Pennsylvania, this 21st day of March, A. D. 1895.

GEORGE B. QUIGLEY. [L.S.]

Witnesses: HUGH E. SHIELDS, R. S. MAGGINI.
